The ornamental design for a shoe heel, as shown and described.

DESCRIPTION

FIG. 1 is a side, perspective view of a shoe heel showing our new design;

FIG. 2 is a bottom, perspective view thereof;

FIG. 3 is a left side view thereof; and,

FIG. 4 is a right side view thereof.

The faded portions within the broken lines and the broken lines themselves illustrate structure or features which form no part of the claimed design.

The drawings include shadows and reflections which indicate contour, not surface ornamentation.
